Patented May 25, 1976

239,996

ROTATABLE SUPPORT BASE FOR A TELEVISION VIEWER OR SIMILAR ARTICLE

Herbert J. Hampel, Philadelphia, Pa., and William A. Hoffman, Collingswood, N.J., assignors to Ultronic Systems Corporation, Moorestown, N.J.

Filed Mar. 24, 1975, Ser. No. 561,637

Term of patent 14 years

Int. Cl. D6—06

U.S. Cl. D6—194

FIG. 1

FIG. 2

FIG. 3

FIG. 4

FIG. 1 is a perspective view of a rotatable support base for a television viewer or similar article showing our new design;

FIG. 2 is a top view;

FIG. 3 is a right side elevational view; and

FIG. 4 is a bottom view.

We claim:

The ornamental design for a rotatable support base for a television viewer or similar article, substantially as shown and described.
